United States Patent Office

Des. 204,740
Patented May 17, 1966

204,740

KNOB FOR DOORS, DRAWERS, AND THE LIKE

Sandi Rae Hershfield, Monrovia, Calif., assignor to Ekco Products Company, Chicago, Ill., a corporation of Delaware

Filed Apr. 28, 1965, Ser. No. 85,218

Term of patent 14 years

(Cl. D10—8)

The figure is a perspective view of a knob for doors, drawers, and the like, showing my new design.

The dominant features of the design reside in the portions shown in full lines.

I claim:

The ornamental design of a knob for doors, drawers, and the like, as shown and described.
